UNITED STATES PATENT OFFICE.

ULYSSES G. SWEENEY, OF CUTLER, CALIFORNIA.

HOLDFAST-NAIL.

1,247,178.

Specification of Letters Patent. Patented Nov. 20, 1917.

Application filed May 8, 1917. Serial No. 167,213.

To all whom it may concern:

Be it known that I, ULYSSES G. SWEENEY, a citizen of the United States, residing at Cutler, in the county of Tulare and State 5 of California, have invented a new and useful Holdfast-Nail, of which the following is a specification.

The device forming the subject matter of this application is a nail, including a thread-10 ed shank, and adapted to be driven by hammer blows, the structure combining the advantages of a common nail and a screw.

The invention aims to provide novel means whereby the ends of the head of the nail 15 will constitute clenching prongs, adapted to engage the material which is entered by the nail, to prevent the nail from rotating after it has been driven.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed, without departing from the spirit of the invention.

In the accompanying drawings:—

30 Figure 1 shows in side elevation, a nail constructed in accordance with the present invention, the same being mounted in a piece of material, the nail being in the condition which it will assume after it has been driven 35 to a seat, and before the clenching prongs have been embedded in the material;

Fig. 2 is a side elevation of the nail, wherein the nail is viewed at right angles to the showing of Fig. 1;

40 Fig. 3 is a top plan of the nail;

Fig. 4 is a view similar to Fig. 1 but showing the clenching prongs embedded in the material;

Fig. 5 is an isometric sectional perspective, showing so much of the nail as lies between the lines *a—a* and *b—b* of Fig. 1;

Fig. 6 is an isometric sectional perspective, showing so much of the nail as lies between the lines *b—b* and *c—c* of Fig. 1;

50 Fig. 7 is a diagrammatic sectional view, the purpose of which is to point out certain of the advantages incident to the nail forming the subject matter of this application, Fig. 7 depicting a nail differing in form 55 from that shown in Fig. 1.

The nail forming the subject matter of

this application is of course made of metal and includes a shank 1 which is twisted or otherwise constructed to form a relatively quick thread 2, the nail being preferably 60 pointed at its entering end, as shown at 3. The nail includes a head denoted generally by the numeral 4. When the head 4 is viewed in top plan, as shown in Fig. 3, the head is of lens shape, and when the head 65 is viewed in side elevation, as in Fig. 1, the head is also of lens shape. The construction of the head is such that, at the ends thereof, bendable clenching prongs 5 are 70 fashioned.

The nail is driven into the material 6 in the usual way, until the nail assumes the position of Fig. 1, under which circumstances, the prongs 5 will be spaced from the material. Since the prongs 5 are spaced 75 from the material, when the parts are arranged as shown in Fig. 1, the prongs may be turned downwardly, by a hammer blow, and be made to enter the material 6, substantially at right angles to the outer surface 80 of the material, without crushing the material unduly. Further, since the outer surface of the head 4 of the nail is convex, a hammer blow, applied, for instance, at the point 8 of Fig. 1, tends to turn the 85 prongs 5 inwardly, to enter the material 6. After the nail has been driven, as shown in Fig. 4, the under side of the head 4 is flattened down against the surface 7 of the material, as indicated at 9, and the prongs 4 90 are embedded in the material 6, as indicated at 10.

It has been pointed out hereinbefore that, since the prongs 5 are spaced from the surface 7 of the material 6, as shown in Fig. 1, before the prongs 5 are turned inwardly, there is no crushing of the material when the prongs 5 enter the same. In Fig. 7, there appears a diagram showing an old form of nail wherein this point is more 100 clearly brought out: In Fig. 7, the material appears at 15 and the numeral 16 indicates the shank of a nail having a common T-shaped head 17, the ends 18 of which lie flat against the outer surface of the material 15. It will be obvious from Fig. 7, that when the ends 18 are bent inwardly, the material 105 will be crushed, and a recess 19 will appear in the material 15, beyond the end of the head 17. This is undesirable for two reasons. First, the hold of the bent end 20 of the head 17 on the material 15 is decreased, 110

and, further, an objectionable recess, as shown at 19 appears beyond the contour of the head 17. Comparing Fig. 7 with Fig. 4, it will be obvious that no opening or recess, 5 corresponding to the recess 19 exists in the material 6, when the device forming the subject matter of this application is used.

Having thus described the invention, what is claimed is:—

10. A nail including a threaded shank having a transverse head, the head appearing tapered toward its ends, when viewed in top

plan, and appearing tapered toward its ends, when viewed in side elevation, to form bendable clenching prongs at the ends of the 15 head.

In testimony that I claim the foregoing as my own, I have hereto affixed my signature in the presence of two witnesses.

ULYSSES G. SWEENEY.
